UNITED STATES PATENT OFFICE.

HERBERT ALEXANDER, WYNDHAM T. VINT, AND ARTHUR IMBERY, OF LEEDS,
ENGLAND; SAID ALEXANDER AND SAID VINT ASSIGNS TO SAID IMBERY.

APPARATUS FOR TEMPERING WIRE.

1,355,521.

Specification of Letters Patent.

Patented Oct. 12, 1920.

Application filed March 3, 1919. Serial No. 280,360.

To all whom it may concern:

Be it known that we, HERBERT ALEXANDER, WYNDHAM THEODORE VINT, and ARTHUR IMBERY, subjects of the King of Great Britain, residing at 1 Charmouth street, Leeds, in the county of York, England, have invented certain new and useful Improvements in Apparatus for Tempering Wire, of which the following is a specification.

10 This invention relates to the hardening and tempering of steel and other metal wire, which is accomplished by heating the wire, passing it through an oil or other cooling bath and repeating the operation.

15 For some purposes it is desired that steel or other metal wire, whether bare or tinned, should be bright after hardening and tempering, but this desideratum has been difficult to obtain when the wire is electrically

20 heated, and practically impossible where a gas or other flame is the heating agent, owing to the rapidity with which the surface of the wire oxidizes when exposed at a high temperature to the air. It has previously

25 been proposed to heat the wire electrically while passing through an inclosed chamber, and then to cool it by passing it through an oil bath; but according to the present invention we effect both the heating and the

30 cooling in the same oil bath, whereby all access of air to the wire while at the critical temperature can be effectually prevented.

The accompanying drawing shows a longitudinal section through an apparatus for carrying out our invention.

In the oil bath, which may be an open topped trough 24, we arrange two pairs of rollers 25 and 26, the distance apart of these rollers being adjustable. The wire 27 passes

40 through an approximately air-tight chamber 28, thence into the trough 24, between the two pairs of rollers, and on leaving the trough passes through another approximately air-tight chamber 30; the trough

45 contains oil, which is always kept at such a level as to immerse thoroughly the traveling wire. Conductors 34 are led to each pair of rollers, and the traveling wire completes the circuit while it is passing between the

50 rollers, in known manner. The wire thus gradually heated, on leaving the second pair

of rollers, continues to travel through the oil for a sufficient distance to reduce its heat as required. At each end of the trough is an oil overflow 31; the oil thus escaping 55 is cooled and pumped back to a pipe 35 above the trough, which delivers it upon the surface of the oil in the trough; by regulating the rapidity of this circulation the oil is kept at a suitable temperature. 60

The chambers at each end of the tank may be provided with glands if found necessary, but in our experiments we have found a washer 33 of asbestos or other fiber surrounding the wire and sealing the apertures of the chambers to be sufficient. 65

We find that the presence of the oil in which the wire and rollers are immersed does not interfere with the making of good contact between the rollers or pulleys and 70 the wire. The first pair of rollers or pulleys 25 may be stationary near the point of entry of the wire, and the second pair 26 may be moved longitudinally in the trough toward or away from the said first pair by a screw 75 36, or other suitable means, in order to vary the proportionate distances and therefore the time during which the wire is being heated between the first and second pairs, and during which it is cooling between the 80 second pair and the exit from the trough.

Two or more similar troughs may be employed in succession in order to repeat the operation where necessary.

We claim as our invention:—

1. In apparatus for tempering wire, a single vessel for holding oil for cooling the wire, pairs of rollers arranged in the vessel and supporting the wire in the oil between them, and means for conducting an electric 90 current to the pairs of rollers to heat the submerged stretch of wire between them. 85

2. In apparatus for tempering wire, a single vessel for holding oil for cooling the wire, pairs of rollers arranged in the vessel 95 and supporting the wire in the oil between them, substantially air-tight chambers at the ends of the said vessel for the wire to pass through, and means for conducting an electric current to the pairs of rollers to heat 100 the submerged stretch of wire between them.

3. In apparatus for tempering wire, a sin-

2
gle vessel for holding oil for cooling the wire, pairs of rollers arranged in the vessel and supporting the wire in the oil between them, means for adjusting the distance apart 5 of the pairs of rollers to vary the length of the stretch of wire to be treated, and means for conducting an electric current to the pairs of rollers to heat the submerged stretch of wire between them.

In testimony whereof we affix our signatures in the presence of two witnesses.

HERBERT ALEXANDER.
WYNDHAM T. VINT.
ARTHUR IMBERY.
